UNITED STATES PATENT OFFICE.

JAMES B. HAMMOND, OF NEW YORK, N. Y.

TYPE-WRITER.

No. 846,027.

Specification of Letters Patent.

Patented March 5, 1907.

Application filed October 21, 1904. Serial No. 229,442.

To all whom it may concern:

Be it known that I, JAMES B. HAMMOND, a citizen of the United States, residing at New York city, New York, have invented certain new and useful Improvements in Type-Writers, of which the following is a specification.

The machine relates to that type known as the "Hammond."

10 In my present form of machine I have sought to so arrange and proportion the parts that the anvil and shuttle may be of larger size than have heretofore been used in this type of machine in order that a larger 15 number of characters may be used on the shuttle than has heretofore been possible.

The invention consists in the features and combination and arrangement of parts hereinafter described, and particularly pointed 20 out in the claims.

In the accompanying drawings, Figure 1 is a plan view of the machine with parts omitted and parts shown diagrammatically for clearness of illustration. Fig. 2 is a sectional view of the machine from front to rear with some parts shown in elevation. Fig. 3 is a detail view showing the means for operating and controlling the ribbon-spool on the opposite side of the machine from that illustrated in Fig. 2. Fig. 4 is a detail view looking from the rear of the machine of the means for controlling and operating the ribbon-feed pawls and detent. Fig. 5 is a detail view of 30 one of the detents of the ribbon-movement.

35 Fig. 6 is a detail cross-sectional view of the frame for the ribbon. Fig. 7 is a sectional view along one of the axes of one of the ribbon-spools. Fig. 8 is a detail view relating to the ribbon-spools.

40 In these drawings, 1 indicates the anvil, and 2 the shuttle carrying the type characters.

The impression is made upon the paper through an inking-ribbon (indicated at 3) by 45 means of a hammer, (not shown, but which is well known in this type of machine.) The ribbon passes along a shield 4, across the face of the shuttle, and its ends are wound upon ribbon-spools 5, which in my present invention are arranged to turn on the horizontally-disposed axis lying in a direction transversely of the machine, so that the ribbon-spools lie at each side of the center frame and turn in vertical planes passing from front to 50 rear of the machine.

The arrangement of parts and the proportions are such that I can employ in my present machine an anvil of large diameter, and consequently the shuttle may be of larger size, presenting a greater surface area for the 60 location thereon of a large number of characters in the same or different languages. The ribbon-spools are driven through toothed wheels 6.

Referring to Fig. 2, it will be seen that the 65 toothed wheel belonging to the ribbon-spool at the left of the machine, Fig. 1, is operated by a pawl 7, carried by a lever or arm 8, which is fixed to a shaft 9. This shaft is journaled in the center framework 10 of the 70 machine. This shaft is provided with an arm 11, fixed thereon, with which is connected a rod 12, extending downwardly and bearing upon a part of the universal space-frame 13, so that each time one of the character- 75 keys is operated the space-frame will cause the operation of the rod 12, and thereby the operation of the pawl 7 through the rock-shaft 9 and arm 8, and this pawl engaging the toothed wheel connected with the ribbon- 80 spool will move the same step by step as the keys are struck. In order to hold the ribbon-spool in moved position, a detent 14 is provided, pivoted on a shaft 15, journaled in the machine-frame, the said detent being ar- 85 ranged in the same vertical plane with and below the pawl 7 to engage the teeth of the wheel 6.

Fig. 3 shows the means for operating the ribbon-spool on the opposite side of the ma- 90 chine, or, in other words, at the right of Fig. 1, and this Fig. 3 represents the positions of the pawl and detent in respect to the toothed wheel at the right of the machine at the time that the pawl and detent at the left of the 95 machine, as shown in Fig. 2, are in active engagement with the toothed wheel on that side of the machine. The pawl for the right-hand side of the machine (indicated at 16) is pivoted to an arm 8', which, like the arm 8 above mentioned, is fixed to the rock-shaft 9, so that as the rock-shaft moves forward the pawl is operated in the direction of the toothed wheel and will turn the same when it is in engagement therewith. Fig. 3, how- 105 ever, shows the pawl held out of engagement, and this is accomplished through its detent 14', which is held in its uppermost or raised position by means of a cam-shaped collar 18 on the shaft 15, said collar having a 110

cut-out portion 19 and a high portion 20. When the shaft 15 is turned so that the high portion 20 is in engagement with the tail-piece 21 of the detent 14', the detent will be raised, as indicated in Fig. 3, and will lift the pawl and hold the same out of engagement with its toothed wheel 6. If, however, the shaft 15 is turned so that the cut-away or low part 19 of the collar is acting against the tailpiece 21, the said detent will be allowed to fall and the pawl will lower into engagement with the ratchet-wheel. The shaft 15 extends from the ribbon-movement on one side of the machine to that on the other side and controls both sets of detent and pawl mechanism. For controlling the mechanism at the left-hand side of the machine the said shaft is provided with an arm 22, having a pin 23, adapted when the arm is raised to engage the detent and lift the same from engagement with the toothed wheel and also to lift the pawl 7. The arm 22 is arranged on the shaft 15 in such relation to the cam-collar 18 that when the cam-collar is lifting the pawl and detent out of engagement with the toothed wheel at the right of the machine the arm 22 is not acting upon the detent at the left-hand side of the machine, and consequently the mechanism here acts to turn the ribbon-movement step by step. The shaft 15 is held in either one or the other of its adjusted positions by means of a spring 24 engaging the notches 25 in a collar 26 on the said shaft 15. The shaft may be turned by a finger-piece 27 at the right of the machine.

The ribbon is guided around pins 28, extending up from a frame or plate 29, which encircles or partly encircles the anvil, the said frame being of angular form, as indicated at Fig. 6, which represents a cross-section of the said frame. At the front of the anvil the frame is pivoted by means of a shaft or rod 30, connected therewith and having its bearings in the frame at 31. A finger-piece 32 is screwed to the plate 29, and by depressing this the ribbon may be lifted from its normal position to the position indicated by dotted lines at x in Fig. 2. In order to hold this frame in either its raised or lowered position, I provide a collar 33 on the shaft 30, said collar having notches, as indicated in dotted lines at 34 in Fig. 2, which notches are engaged by a spring 35, fixed at 36 to a suitable portion of the frame. The ribbon-shield 4 is carried at the rear ends of a wire loop 37, which partly encircles the anvil and shuttle and at its front is bent at 38 and pivots in bearings 39, formed on the plate 32. The loop or wire rests on the plate 29; but near the rear portion the bottom flange of the plate is cut away at 40, and at these points the wire loop is exposed on each side of the shuttle or anvil to the action of the arms 8 8', which have rearward extensions provided

with bent ends 41, passing beneath the wire 65 loop.

As before stated, each time a letter-key is operated the arms 8 8' will be moved to effect the ribbon-movement, and these arms will, in addition to this function, perform another 7c function in connection with the wire loop of the ribbon-shield—that is to say, their ends 41 will engage the wire loop and lift the same sufficiently to raise the ribbon up to the plane of the printing-point, so that the impression can be made through the ribbon, and this having been accomplished the arms 8 8' will fall, allowing the wire loop to drop from the printing-point, thus providing a machine having the feature of visible writing. 80 In order to provide for stopping the upward movement of the wire loop, stops are provided at 42, extending from the pins 28 over a portion of the wire loop.

The escapement in my present machine is 85 substantially the same as that well known in the Hammond type-writer; but instead of operating the ribbon-movement for the visible writing each time either a letter-key or the space-key is operated I provide means 90 whereby the space-key can be operated alone and without operating the sight attachment. For this purpose, in addition to the arm 43 extending from the universal space-frame to the escapement mechanism, I provide connections between the space-key and the said escapement mechanism, whereby the said space-key may be operated without affecting the sight attachment. This connection consists of an arm 44, connected with the space-key frame 45, which arm is pivoted to a lever 46, pivotally supported at 47 to the frame and having a bent rear end 48 overlying the arm 49, which is connected with the escapement mechanism. This arm also is operated 100 by the arm 43 of the universal space-frame. It will be seen from this construction that when the space-key alone is operated the escapement mechanism will be operated without operating in any way the sight attachment. 105 The lever 46 is provided with an upwardly-extending finger 50, adapted to operate the hook 51, pivoted at 52 to the frame, which hook controls the operation of the hammer; so as to prevent the same from 110 striking the blow when the space-key is operated. The ribbon-spool comprise the disks 53, secured to a sleeve 54, which fits on the extended hub 55 of the toothed wheel 6. These parts are supported by a pin 56, having a portion passing through the arm 57, wherein it is held by a nut 58. The toothed wheel and the ribbon-spool are held together to move as one by a pin 59. In order to provide an adjustable friction device to restrain 115 the rotary movement of the spool, I provide a cone-shaped spring 60, the base of which fits against the end of the hub 55 and the 120

125

apex of which is borne upon by the part 61 of a thumb-nut 62, which is screwed into the central pin 56. By tightening or loosening this thumb-nut the frictional pressure between the spring and the hub will be increased or diminished, and thus the spool will be put under more or less restraint in turning on the pin 56.

I claim as my invention—

- 10 1. In a type-writer of the class employing a shuttle, and an anvil, and in combination with an anvil and shuttle of enlarged size, a ribbon-movement including ribbon-spools arranged at the sides of the anvil and turning upon horizontal axes, said spools revolving in planes substantially tangential to the anvil substantially as described.
- 15 2. In combination, in a type-writer with the anvil and shuttle, a ribbon-movement including ribbon-spools at the side of the anvil turning about horizontal axes, said axes being coincident, and said spools turning in planes substantially tangential to the anvil substantially as described.
- 20 3. In combination, shuttle means, ribbon-spools arranged on horizontal axis adjacent to shuttle means and turning in planes substantially tangential to the anvil and means for directing the ribbon first vertically from the spools, then rearwardly and then horizontally in rear of the shuttle means, substantially as described.
- 25 4. In combination, with printing mechanism, ribbon-spools arranged on horizontal axis adjacent thereto, and a frame inclosing the printing mechanism at the front and pivoted at its front end and partially embracing the printing mechanism at the rear for guiding the ribbon.
- 30 5. In combination with printing mechanism including a shuttle, a ribbon-movement including ribbon-spools and ribbon-shield, a loop closed at its front end pivoted at its front end and carrying the ribbon-shield, means for operating the ribbon-spools and means at the front end for lifting the loop to raise the ribbon-shield and ribbon, substantially as described.
- 35 6. In combination, with the shuttle and its anvil, a pivoted member partly embracing the same, and a sight attachment including guiding means for the ribbon movable in respect to the pivoted member, said attachment being carried by the said plate.
- 40 7. In combination with the shuttle, an anvil, a pivoted member partly embracing the same, a ribbon-shield, means carrying the same and pivotally supported on the pivoted member, and means for lifting the shield-carrying means and constituting a sight attachment, substantially as described.
- 45 8. In combination with the shuttle, an anvil, a pivoted member partly embracing the same, a loop pivoted to the member at the

front end thereof, a shield carried by the said loop, means for directing the ribbon to the shield and means for raising and lowering the loop.

9. In combination, with the printing mechanism, a ribbon guide or shield to hold the ribbon with its flat side in a vertical plane, a movable support therefor to move the shield and ribbon vertically, a ribbon-spool, a ratchet-wheel, a pawl and an arm carrying the said pawl and adapted to operate the movable support of the ribbon-shield, substantially as described.

10. In combination with printing mechanism, a ribbon guide or shield, a movable support therefor, a ribbon-spool arranged with its axis horizontally to turn in a plane tangential to the anvil, a pawl for turning the ribbon-spool and an arm carrying the said pawl and independent of the shield-support, said arm acting upon the ribbon-shield support to move the same, substantially as described.

11. In combination, with printing mechanism including a shuttle and an anvil, ribbon-spools arranged on horizontal axis on opposite sides of the machine and turning in planes substantially tangential to the anvil, a rock-shaft extending transversely of the machine and beneath the anvil, arms on the said rock-shaft, pawls carried by the arms for engaging the toothed wheels, detents and means for controlling the position of the detents and pawls at opposite sides of the machine including a second rock-shaft extending parallel with that first mentioned and also beneath the anvil, substantially as described.

12. In combination with printing mechanism, a ribbon-movement having means for raising and lowering the ribbon and constituting the sight attachment, a universal frame, the keys for operating the same, connections from the sight attachment to the universal frame, carriage-space mechanism operated from the said universal frame, a space-key and connections between the said space-key and the escapement mechanism independent of the universal spacing-frame, substantially as described.

13. In combination with a ribbon-spool, a toothed wheel a pin upon which the said parts turn, and a friction device comprising a conically-shaped spring arranged to press upon the interior of the hub of the spool, and a nut for pressing the same against said hub, said nut being supported on the axis or pin, substantially as described.

14. In combination with the shuttle and anvil, a pivoted member carrying a guide for the ribbon, a pivoted ribbon-shield support movable independently of the said member and also movable with said member, and means for automatically moving the ribbon-

shield support as the keys are operated, substantially as described.

15. In combination in a machine of the class described, the anvil, a ribbon-shield, a pivoted support therefor, a member pivotally supported and when raised serving to raise also the pivoted support of the ribbon-shield, and means for automatically moving the

shield and ribbon as the keys are struck, substantially as described.

In testimony whereof I affix my signature in presence of two witnesses.

JAS. B. HAMMOND.
